UNITED STATES PATENT OFFICE.

LUDWIG EIRICH AND JOSEPH EIRICH, OF HARDHEIM, GERMANY, ASSIGNEES TO THE FIRM OF MASCHINENFABRIK GUSTAV EIRICH, OF HARDHEIM, GERMANY.

MEASURING AND CONVEYING DEVICE FOR CONCRETE AND OTHER MATERIAL.

1,268,553.

Specification of Letters Patent.

Patented June 4, 1918.

Application filed May 27, 1915. Serial No. 30,814.

To all whom it may concern:

Be it known that we, LUDWIG EIRICH and JOSEPH EIRICH, both citizens of the German Empire, and residents of Hardheim in the 5 Grand Duchy of Baden, Germany, with the post-office address Walldürnerstrasse 65-66, have invented new and useful Improvements in or Relating to Measuring and Conveying Devices for Concrete and other Material, of 10 which the following is a specification.

In connection with endless conveyers it has already been proposed to construct the transverse walls of the individual sections or compartments in a movable manner or to 15 make the bottom parts thereof movable so that at the delivery point the material may be completely removed from the individual sections and the conveyer may, if desired, be cleaned by means of a scraper or wiper. According to this invention a conveying device 20 of the above kind is so arranged that it may simultaneously be employed to measure the material conveyed by it. To this end the guides for the movable transverse walls or 25 bottom parts are made adjustable particularly at the point at which the conveyer passes through the feed receptacle so that the transverse walls or bottom parts may at the delivery point be positioned higher or 30 lower according to the quantity of material required to be conveyed during one complete travel of the conveyer.

If desired, the device may also be so constructed that a reciprocating slide is used 35 in the place of a conveyer band, which slide is fitted with a number of compartments provided with bottom flaps, which latter are capable of being lowered to a determined adjustable depth for the purpose of receiving 40 from the feed receptacle a determined quantity of material. The material thus received by the compartments is intermittently located in front of wipers arranged above the slide and then conveyed further.

45 Several such conveying bands may be arranged side by side or several feed receptacles may be located above each band.

Several constructional forms of a device according to this invention are illustrated 50 by way of example in the accompanying drawings, in which:—

Figure 1 represents a lateral view of one form of the conveyer which is arranged on an appropriate carriage and may be tipped 55 to any desired oblique position.

Fig. 2 is a longitudinal section of Fig. 1, and

Fig. 3 is a top plan view thereof.

Fig. 4 shows in partial section a second constructional form in which the conveyer 60 band is composed of individual curved plates so as to enable the conveyer to form a precise cylindrical surface at the reversing points.

Figs. 5, 6 and 7 show diagrammatically 65 various arrangements and positions of a conveyer arrangement.

Fig. 8 shows a conveyer arrangement for the simultaneous conveyance of stones, sand, 70 mortar and the like.

Fig. 9 shows a constructional form in which use is made in the place of movable transverse walls of movable bottom parts in the form of flaps of corresponding compartments, and

Figs. 10 and 11 show a further constructional form of a reciprocating slide in two 75 different positions.

Referring first to Figs. 1 to 3, it will be seen that a frame 3 is pivoted at 2 on a carriage 1 and is provided with a driving shaft 4 carrying a pair of sprocket wheels 5 adapted to be driven by any known driving mechanism. The whole frame 3 may be tipped about the shaft 2 from the position 80 shown in dotted lines to that shown in full lines or any other intermediate position by means of a hand wheel 6 which through the agency of a worm gear 7 operates a chain 9 secured at 8 to the framework. An endless 90 band-like conveyer 11 is adapted to travel around the sprocket wheel 5 on the one hand and about a curved guide 10 on the other. This conveyer consists of a number of individual sections hinged together by pins 12. 95 These sections or compartments are provided with lateral walls 13 carrying sectors 14 so shaped as to completely close the spaces or crevices produced between the lateral walls during the travel of the compartments over 100 the pair of the sprocket gears 5 and over the guide 10 and thereby to prevent material from dropping out or from collecting between the compartments.

The material is supplied from a hopper 105 15 traversed by the conveyer and the delivery takes place at 16 where a wiper or scraper 17 is arranged for the purpose of cleaning the bottom parts and lateral walls of the conveyer in a continuous manner.

Arranged in the individual sections are slots through which the transverse walls 18 (see Fig. 2) are adapted to move. These transverse walls are secured to members 20 rotatable about pivots 19 and provided with rollers 21 adapted to travel along a guide 22 adjacent to the conveyer. This guide is so arranged as to be adjustable below the hopper 15 thereby enabling the transverse walls 18 to project to a determined extent above the conveyer band and, therefore, to receive a determined quantity of material from the supply hopper. On the remaining portion of the ascending band the guides are stationary and more closely arranged to the band in order that the transverse walls may at these points still further project and that the material may be prevented from falling out.

For the descending portion of the band, that is to say, on its idle side, the guides are so arranged as to cause the transverse walls to be completely retracted and, consequently, to enable the wiper 17 to completely clean the band and the lateral walls.

The adjustable portion of the guide 22 located below the hopper 15 is marked 23. It is provided at its lower end with an incline 24 which is movable in a block 25 and on its upper end is provided with a rack 26 adapted to engage with a small toothed wheel 27. At this point a block 28 is again arranged to form a bearing.

Mounted on the shaft of the toothed wheel 27 is a hand wheel 28^a by means of which the toothed wheel 27 may be rotated and thereby the rack 26 and the guide portion 23 adjusted at will. By this displacement due to the oblique parts referred to, this guide portion will be set at a higher or lower level as will be readily understood.

The incline 24 also serves to cause the individual rollers 21 to ride up the adjustable guide portion 23 from the lower guide portion 29 at the lower reversing point. For the curved guides 10 a sprocket wheel similar to sprocket wheel 5 may be substituted.

In the constructional form shown in Fig. 4 the arrangement is similar except that the individual bottom parts 11 of the compartments are not straight but are curved in order to enable the conveyer at the reversing points where it travels over the sprocket gears or over the curved guides to assume a completely smooth cylindrical surface capable of being easily cleaned by a wiper.

Fig. 5 shows diagrammatically the conveyer constructed in a triangular form in which the individual sides of a triangle may be of any desired length and form any desired angle one with the other. Fig. 6 shows the conveyer band in horizontal and Fig. 7 in a vertical arrangement. Fig. 8 shows a portion of the conveyer band in vertical arrangement, the construction being

such as to enable the conveyer to carry simultaneously, for instance, bricks 30 and sand or mortar 31.

According to Fig. 9 which shows a section of another modification, the bottom parts of the conveyer are adjustable instead of the transverse walls thereof. In this case the individual sections of the conveyer are constructed in the form of flaps 31 rotatable about 32 and carrying rollers 33 running along an appropriate guide 34. The front walls 35 are permanently secured so that compartments 36 are produced into which the material may drop from the hopper 15. The discharge of the compartments is effected in this case by the guide 34 being placed nearer the conveyer at the delivery point whereby the flaps 31 are caused to rotate about their pivots 32 and are thus moved flush with one another, as indicated in the lower part of Fig. 9, so that at these points the band again forms a continuous surface capable of being readily wiped by a scraper. On the idle side of the conveyer band the flaps are all raised until they enter the hopper 15 as indicated at 37 where it will also be seen that the corresponding part 38 of the guide for the rollers 33 is located at a higher level.

Instead of constructing the transverse walls in the form of arcs they may be straight or they may consist of corrugated sheet metal or the like.

Other means may, of course, be employed for adjusting purposes in the place of guide rollers and corresponding guides of the kind described. For particular purposes the transverse walls may be in the form of individual prongs or rakes.

Now what we claim and desire to secure by Letters Patent is the following:

1. In conveyers of the character described, a continuous trough comprising segments, said segments being pivotally joined together, in combination with a plurality of movable walls adapted to co-operate with said segments so as to constitute a plurality of receptacles and adjusting means for the movable walls whereby the capacity of the receptacles may be varied.

2. In conveyers of the character described, a continuous trough comprising segments, said segments being pivotally joined together, some of said segments having openings, in combination with means comprising a plurality of movable walls adapted to co-operate with said segments through said openings so as to constitute a plurality of receptacles of variable capacity and adjusting means controlling the position of said walls.

3. In conveyers of the character described, a continuous trough comprising segments, said segments being pivotally joined together, in combination with a plurality of

movable walls adapted to coöperate with said segments so as to constitute a plurality of receptacles, rollers for said movable walls and means coöoperating with said rollers whereby the capacity of the receptacles may be varied.

4. In conveyers of the character described, a continuous trough comprising segments, said segments being pivotally joined together, in combination with a plurality of movable walls adapted to coöperate with said segments so as to constitute a plurality of receptacles, a rotatable member connecting said segments and said movable walls, rollers for each rotatable member and means coöoperating with said rollers whereby the capacity of the receptacles may be varied.

5. In conveyers of the character described, a continuous trough comprising segments, said segments being pivotally joined together and having openings in combination with a plurality of movable walls adapted to coöperate with said segments so as to constitute a plurality of receptacles, a sector secured to said segments, a rotatable member connecting said segments and said movable wall, a roller for said rotatable member and adjustable means coöoperating with said roller whereby the capacity of the receptacles may be varied.

6. In conveyers of the character described, a continuous trough comprising segments, said segments being pivotally joined together and having openings in combination with a plurality of movable walls adapted to coöperate with said segments so as to constitute a plurality of receptacles,

a sector secured to said segments, a rotatable member connecting said segments and said movable wall, a roller for said rotatable member, guide means coöoperating with said roller and a rack to adjust said means to vary the capacity of the receptacles.

7. In conveyers of the character described, a continuous trough comprising segments, said segments being pivotally joined together, in combination with a plurality of movable walls adapted to coöperate with said segments so as to constitute a plurality of receptacles, means to drive said trough and adjustable guides coöoperating with the movable walls whereby the capacity of the receptacles may be varied.

8. In conveyers of the class described, a continuous movable trough comprising segments pivotally joined together, transverse walls at the ends of the segments two of which have a single wall in common, the height of said walls with reference to the bottom of the trough being variable whereby a plurality of receptacles of variable capacity may be constituted, and means fixed with reference to but coöoperating with the trough as it moves so as to control said wall height.

That we claim the foregoing as our invention, we have signed our names in presence of two witnesses, this first day of May A. D. 1915.

LUDWIG EIRICH.
JOSEPH EIRICH.
